UNITED STATES PATENT OFFICE.

WILLIAM M. BROWNELL, OF BROOKLYN, NEW YORK, ASSIGNOR OF THREE-FOURTHS
TO ARTHUR N. HOOD, OF NEWTON, MASSACHUSETTS, AND JOHN T. NIGHTINGALE,
OF BOSTON, MASSACHUSETTS.

DRYING-MACHINE.

1,242,518.

Specification of Letters Patent.

Patented Oct. 9, 1917.

Application filed May 1, 1916. Serial No. 94,586.

To all whom it may concern:

Be it known that I, WILLIAM M. BROWNELL, a citizen of the United States, residing at the borough of Brooklyn, county of Kings, 55 State of New York, have invented a certain new and useful Improvement in Drying-Machines, of which the following is a specification, reference being had therein to the accompanying drawings.

10 My invention has for its object a new and improved machine or dryer for use in extracting an evaporable fluid such as water from an adhesive, plastic or semi-fluid substance. One substance of this kind is green 15 curds formed by precipitation from butter-milk or skimmilk in the manufacture of casein. Another substance is the residue left in the process of refining sugar, and which is sometimes referred to as "sugar-mud." 20 The machine embodying my invention is also capable of a variety of other uses not necessary to be mentioned in detail here.

Before describing the construction of the machine, it may be stated that the material 25 is rendered homogeneous and is forced under pressure through a plurality of drying tubes or pipes which are subjected by suitable means to heat sufficient to convert the evaporable fluid into vapor or steam and as 30 I believe to form a layer thereof between the semi-solid matter and the walls of the tube which keeps the material being dried from adhering to the walls of the tube and from burning. To avoid the escape of the steam 35 and to prevent the pressure produced by the expansion of the fluid into vapor from forcibly ejecting the material and thus reducing the pressure in the tube below the necessary point, I form suitable constrictions in 40 the pipes and thereby impede somewhat the progress of the material through the drying tubes.

By regulating the temperature in the tubes carefully, the material may be caused to 45 emerge from the machine in almost any state of dryness required. The moisture passes off, into the air by the sudden expansion caused by the release of pressure as it emerges into the open air. I also slice 50 through the material at frequent intervals just as it enters the drying tubes, as I believe this treatment facilitates the drying.

The invention will be fully understood from the following description taken in connection with the accompanying drawings 55 and the novel features thereof are pointed out and clearly defined in the claims at the close of this specification.

In the drawings, Figure 1 is a longitudinal vertical section of a machine embodying my 60 invention.

Fig. 2 is a section on line 2, 2 of Fig. 1 looking in the direction of the arrows.

Fig. 3 is a section on line 3, 3 of Fig. 2 looking in the direction of the arrows. 65

Fig. 4 is a detail of the stuffing box construction.

Fig. 5 is a detail of a device for forming a longitudinal bore in the material as it emerges. 70

Fig. 6 is a view of said device in perspective.

Referring now to the drawings, at 11 is shown the hopper into which the material to be operated upon is fed. At 12 is shown 75 a body or casing which incloses the forcing mechanism or power feed by means of which the material is forced under heavy pressure through the dryer. In the machine shown in the drawings this is a feeding worm or screw 13 mounted on a shaft 14 and driven by suitable means as a pulley 15. It will be understood that I do not limit myself to this particular form of mechanism for propelling the material forward although I believe it to be the best for the purposes which I contemplate. 85

At 16 is shown a perforated plate having therein a series of constricted passages 17 (see Fig. 3) which lead to the drying tubes 90 18. The perforated plate 16 is provided with a flange 19 which is engaged by a flanged collar 20 which screws onto the body 12 of the propelling mechanism. At 21 is shown a cutter or knife having one or more blades. 95 It is mounted on the end of the shaft 14 so that it revolves therewith, with its face in contact with the end face of the perforated plate 16. This cutter slices through the material at frequent intervals just as the material is being forced into the constricted passages 17 and has an important effect on the 100 drying operation. I find that by slicing through the material at intervals, moisture

is brought to the surface of the cut, as is noticeable when an apple is sliced with a knife, and this tends to liberate the moisture and to expedite the drying. It also tends to cause the final product to separate into small pieces like flakes or laminæ which is desirable in many cases.

The drying tubes 18 are of a length determined by the nature of the substance to be operated upon and the temperature to be employed, and are preferably brazed into a plate 22 which is secured by screws 23 or other suitable means to a head 24 into which the perforated plate 16 is itself screwed. A packing 25 serves to make a tight joint.

The drying tubes 18 diverge as shown in Fig. 1 so that there is a greater space separating them at the outlet end and permitting a better flow of steam about this part 20 of the tubes. The tubes 18 pass through holes in a head 26, a tight joint between each of the tubes and the head being made by means of a suitable gland 27 and a packing 28. This permits the drying tubes to 25 move slightly relatively to the heads 24 and 26 without producing leakage. The drying tubes 18 project through the head 26, and are provided with constricted nozzles or tips 29, the orifices of which are at different 30 distances from the head 26, the orifices of the top tubes being at a greater distance than those of the bottom tubes, as will be seen in Fig. 1. This permits the strips of material which emerges from the several 35 orifices to fall clear and not to interfere with each other.

The drying tubes 18 are surrounded by a casing 30 suitably secured to the two heads 24 and 26 as by flanges 31, and 32. A 40 suitable heating medium as for instance steam under pressure is supplied to the interior of the casing 30 by the pipe 33 controlled by the valve 34. The steam passes out by the pipe 35 controlled by the valve 36. At 37 and 38 are shown pipes by which water of suitable temperature may be introduced into the dryer when it is being put into or out of operation.

At 39 is shown a conveyer on which the 50 dried material falls, and at 40 is shown a knife roll for cutting or breaking up the strips of dried material.

In Figs. 5 and 6 there is shown a fixed member 41 supported in a ring 42 by means 55 of two bars 43 which serves to form a hole in the strip of material and also to take the place of the constriction by occupying part of the space in the bore of the drying tube. This is for use when it is desired to 60 produce a tubular strip of material. It may also be used to take the place of the constricted tip 29.

In the operation of my machine, steam of a pressure to give the necessary degree of heat is admitted to the casing around the

tubes 18, and then the material to be dried is placed in the hopper 11 and the machine is started. It is forced forward under heavy pressure by the screw 13 which impels it through the perforated plate 16. Just before it enters the holes in the perforated plate, it is sliced through by the knife 21 for the purposes previously explained. The constrictions in the passages 17 retard the movement of the material so 75 that the tubes will be filled entirely full. The steam in the jacket heats the tubes very hot and converts a part of the moisture in the material into steam which I believe forms a protective layer between the material and the inner surface of the drying tubes. But whatever is the action, I find that the material does not burn and does not adhere to the tubes, and that when it emerges into the atmosphere the moisture 85 immediately is dissipated into the atmosphere and the material is found to be dry.

While I have shown herein a steam jacket as the means for heating my drier, it will be understood that any suitable heating 90 medium or direct heat may be employed. It will also be understood that the material may be passed through the machine more than once if it is found desirable to dry it by stages rather than by a single operation; 95 also that this may be repeated as long as the material remains in a sufficiently plastic condition.

What I claim is:

1. The combination of a drying tube having a constriction near the discharge end, means for heating the drying tube, and means for forcing the material under pressure through said drying tube. 100

2. The combination of a drying tube having constrictions one near the intake end and one near the discharge end, means for heating the drying tube and means for forcing the material under pressure through 105 said drying tube. 110

3. The combination of a drying tube, means for heating the drying tube, means for forcing the material under pressure through said drying tube, and a knife to slice through the material before it enters 115 the drying tube.

4. The combination of a plurality of drying tubes, a heating jacket surrounding said drying tubes, and means for forcing the material to be dried through the said tubes, 120 said pipes diverging toward the discharge end.

5. The combination of a plurality of drying tubes, a heating jacket surrounding said drying tubes, and means for forcing the material to be dried through said tubes, the discharge orifices of the said tubes being arranged so that the orifices of the top tubes project beyond those of the tubes just below. 125

6. The combination of a series of drying 130

tubes, a steam jacket surrounding them composed of two heads and a casing, a perforated plate the orifices of which leading into said drying tubes said perforated plate being screwed into one of said heads, a second perforated plate to which said tubes are each rigidly secured, said second perforated plate being secured to said head, and said tubes passing through said second

head to allow for difference of expansion 10 between the tubes and the said casing.

In testimony whereof I affix my signature, in presence of two witnesses.

WILLIAM M. BROWNELL.
